LAMP ELEMENT

Maurice K. Kaplan, Chicago, Ill., assignor to
 Nellie J. Kaplan Company, a corporation of Illinois

Application February 27, 1939, Serial No. 259,821

3 Claims. (Cl. 240—81)

This invention relates to an improved lamp element, and more particularly to a lamp element for incorporation in floor and other lamps to serve as a safety lamp.

- 5 Safety lamps have heretofore been provided in the base of lamps, consisting of a small globe hidden in a large insert under the base, and generally enclosed. These are difficult to remove when burnt out and also frequently overheat, 10 with possible severe damage. In the present invention a small safety lamp is provided in the upper portion of the lamp, and in a manner such that it may readily be removed, and so ventilated that no overheating is possible. Moreover, 15 by being positioned away from the base, even if overheating occurs, there is substantially no possibility of fire. It can be seen from any point in the room.

The invention is illustrated in the drawing in 20 which Figure 1 is a fragmentary elevation of a lamp showing the safety lamp unit; Figure 2 is a vertical section taken along the line 2 of Figure 3; Figure 3 is a cross-section taken along the line 3 in Fig. 1.

25 The safety light element 10 comprises two elements, a socket member 11 and a supporting member 12. The socket member is provided at the bottom with a screw threaded opening 13 adapted to be secured to the correspondingly threaded tubular column 14 of the lamp 15. Within the base of the socket member is a socket 16 provided with suitable electrical connections. The socket is mounted upon a nipple 40 which is inserted in the column 14 and held in place by 30 the collar 41. A pair of wires 17 in parallel with the socket connection is carried upwardly to provide current for the lamp proper.

The socket member is considerably enlarged 35 above the socket to provide space for a light bulb 18, and also considerable excess space, so that 40 the fingers may be inserted and unscrew and grasp the bulb. In the vicinity of the bulb a large number of small perforations 19 is provided for cooling ventilation and for visual and decorative effect.

45 A similar line of perforations 20 is carried about the top of the socket member.

The top of the socket member is substantially flat, but four upstanding lugs 21 are provided 50 with grooves 22. Into these grooves the tongues 23 of the supporting member 12 fit.

The supporting member 12 includes a threaded opening 24 at the top which interfits with the correspondingly threaded lamp member 25. Immediately below this point the member 12 widens

5 to correspond to the socket member, and is penetrated by four openings 26, at least one of which should be large enough to permit ready removal of the bulb 18. These openings divide the support into four leg portions 27, each of which has a tongue 23 which interfits with the groove 22 to lock the supporting and socket members together.

One of the legs 27 is provided on its underside with a channel 42 within which the wires 17 are 10 concealed. The channel is preferably enclosed with an opening at each end, but it may be closed at the sides only and suitable anchoring means provided for the retention of the wires therein.

15 In assembling the lamp the socket 16 is wired and installed, and the wire 17 threaded completely through the lamp, after which the socket and supporting members are interlocked, and are preferably then fixed in position by pins or 20 screws 30 which are inserted in suitably drilled openings.

The bulb 18 may be removed by inserting the fingers in the openings 26.

25 The switch 43 controls the safety lamp. It may be made to control all the lights, separately or in combination, if desired.

The complete lamp is strong, safe, and very decorative. It also is easily assembled.

30 Obviously, other interlocking means may be adopted and the tongue and groove elements may be reversed.

I claim:

1. A safety lamp element adapted for incorporation in a floor lamp and comprising; a lower member adapted to be mounted on the standard of a floor lamp, and provided with a plurality of small perforations for diffusing light and having an enlarged annular upper edge portion, an upper member provided with means for supporting the main illuminating portion of the lamp, and having an enlarged annular lower edge portion, the two enlarged edge portions being secured in abutment relationship, socket means for holding a miniature light in the lower member, and the upper member having a plurality of holes approximately the diameter of the light, whereby the light may be removed by inserting fingers in the holes and removing the light through one of the holes.

2. A floor lamp including; a standard and a safety lamp element comprising; a lower member adapted to be mounted on the standard and provided with a plurality of small perforations for diffusing light and having an enlarged an-

50

55

nular upper edge portion, an upper member provided with means for supporting the main illuminating portion of the lamp and having an enlarged annular lower edge portion, the two enlarged edge portions being secured in abutment relationship; socket means for holding a miniature light bulb in the lower member, and the upper member having a plurality of holes approximately the diameter of the light bulb

whereby the light may be removed by inserting fingers in the holes and removing the light through one of said holes.

3. A floor lamp as set forth in claim 2 in which the upper and lower members of the safety lamp element comprise the sole supporting means for the main illuminating portion of the lamp. 5

MAURICE K. KAPLAN.
